UNITED STATES PATENT OFFICE.

ALBERT C. FISCHER, OF CHICAGO, ILLINOIS.

EXPANSION-CONTRACTION JOINT.

Application filed January 3, 1922, Serial No. 526,742. Renewed February 1, 1926.

Heretofore, in concrete paving where contraction was to be provided for it has been the practice to insert a piece of metal longitudinally or transversely below the surface, so that when the concrete block or slab is fully poured and completed the contraction joint is not visible at the surface. After the concrete sets and contracts the function of these pieces of metal is to cause a very fine crevice to develop thru the entire slab, so that it becomes visible on the surface, and functioning in this way it is styled a contraction joint.

Further development in this style of allowing for expansion and contraction in concrete pavements can be made in which a wedge or angular formation is provided, so that the projections developing in one concrete slab, by reason of filling in these projections in the contraction joint, penetrate the other slab so that resistance is caused to any lifting action on the part of the concrete slabs. Some of these formations have been angular and some half hexagonal in shape, with straight flanges extending on either side in a vertical position when placed. These contraction joints, while causing the crevice to form along a straight line across the concrete slab or in the surface above which the contraction joint is inserted, do not prevent the ingress of water, street acids and the like, which would tend to hastily corrode the metal contraction joint, and also enter the subsoil underneath the slab, keeping the subsoil and the crevice in a constantly wet damp condition.

My invention provides for an improved contraction joint which has many advantages, and which also provides for the waterproofing of the contraction joint automatically, as well as allowing a better pivot motion on the projection anchor in the adjoining slab. This is caused by the insertion of a bituminous slab of varying thickness, depending upon the requirements. The contraction joint flanges are imbedded in the bituminous slab on either side of the projecting center. This not only tends to preserve the metal flanges but also has a tendency to protect the projection, because in expanding in warm weather some of this bituminous material will find its way along the surface of the uncovered metal.

It may be readily understood, of course, that a metal contraction joint may be coated with paint or bituminous material, in addi-

tion to the projecting slabs of bituminous material acting both as expansion and contraction joints.

Expansion joints have usually been placed so that the upper edge of the joint was visible on the surface of the pavement, and in many cases was allowed to project above the surface, so that the traffic would form a sort of mushroom top over the crevice.

It can be readily understood that the purpose of this invention is to totally submerge both the contraction and expansion parts of this joint beneath the surface, so that when the concrete is finished and poured it will not be visible on the surface but will accomplish the same function, in causing a crevice to form across the surface, due to contraction. It will further function by waterproofing this crevice from within, and upon expansion of the bituminous material, and also the pavement, it will cause the asphaltic substance to work its way up through the crevice, so that after a hot period the bituminous material may often work its way to the surface, while the base part will have a tendency to prevent moisture from coming up, filling the crevice from below, and in this manner the entire crevice will be kept waterproof, and at the same time perform both the functions of an expansion joint and a contraction joint.

The invention can best be understood by referring to Figure 1, in which (a) represents an expansion joint placed over the flanges (c) of the metal contraction joint (b), and in which (b) is the nose projecting into the adjoining slab.

The concrete is poured on either side and over the joint, so that the formation of the slab will follow the lines of the joint. (b) may be of any type of metal, and may be either flexible or rigid. It may also be coated with a protecting coat or suitably finished to prevent adhesion to the slab of concrete.

In Figure 1 the projection of the contraction joint (b) is semi-circular, so that the slab adjoining this contraction joint may pivot on the concrete and metal formed by the outline (b), and so that there will be some room for sliding motion by reason of the expansion joint (a) fitted over the flanges (c), the effect in the paving or construction will be the same for contraction purposes as is caused by the similar insertion of the metal, and in addition thereto will perform better pivot action, will allow for expansion as well

as contraction, will waterproof the crevice from within, and will extend itself automatically under pressure along the lines of the contraction joint (b); thus preserving the metal and keeping the entire joint waterproof. I believe it is entirely new to waterproof a joint from within, so that the material will find its way thru to the surface upon the development of crevices in the pavement.

10. In Figure 2 I show an angular, flexible expansion contraction joint, flexible at the point (b'), having flanges (c) imbedded in bituminous expansion joint (a). The purpose of this arrangement is for better conditions for packing.

Figure 3 illustrates the same joint as shown in Figure 2 expanded when set in position and when ready to pour the concrete.

20. Figure 4 illustrates a method of preparing the joint so that the expansion joint (a) mounted on the flange (c) can be packed in a superposed position, as shown in Figure 5. When placed in position for pouring concrete the superposed layers (a) are opened up, as in Figure 4, the joint then functioning the same as that shown in Figure 1.

Figure 6 represents an expansion contraction joint formed in a manner to allow the filling of the circular part (b^3) with concrete, and is surrounded on its outer surface by expansion joint (a^1). The flanges (c^1) are in this instance left uncovered, and the slabs are poured against the surface, and are given a core about which to pivot. The bituminous expansion joint, upon compression, will expand along the flanges (c^1) and keep the joint superposed.

Figure 7 indicates a straight piece of metal functioning as a contraction joint, and having attached to its center on either side, walls of expansion joint material.

Figure 8 illustrates the same form as in Figure 1, except that the expansion joint (a) instead of being on the flange of the contraction joint (b) is placed about the center of the semi-circular section (b), the flanges (c) being protected merely by paint or other suitable substance.

50. In Figure 9 the contraction joint (b^4) takes on a semi-hexagonal shape, with two extending flanges (c), the expansion joint (a^3) being placed upon the inner face of (b^4).

55. In Figure 10 we have the same arrangement of the expansion contraction joint as in Figure 1, with the exception that holes (d) are punched thru the joint to allow the insertion of steel bars, metal pins, or the like, for the further joining together of the concrete slabs.

It may be readily understood that there may be many variations of this expansion contraction joint, and that it may exist even in a very small form, by inserting an expansion

joint so that when the concrete is poured the expansion joint does not come thru to the surface of the slab.

In this case the expansion joint would function as a contraction joint and would perform the same service upon pressure and expansion, in waterproofing the crevice, the main difference being that it would not provide an insert into the adjoining slab. The appearance of this joint when imbedded would appear as in Figure 11. When immediately finished would take the form as in Figure 12. When contraction has taken place and upon further expansion the bituminous material would work its way to the surface as shown in Figure 13.

Again referring to Figure 1 (aa) are expansion joints which may be made up of any suitable material for that purpose. These expansion joints are primarily constituted of bituminous materials and mixed with fibre, cellular material etc. (b) illustrates a contraction joint with flanges (c) imbedded in the expansion joint (aa).

Figure 2 illustrates two expansion joints (aa) having imbedded therein the flanges (cc) of a contraction joint (b^1) formed of flexible material for the better packing of the joint in a small space.

Figure 3 illustrates expansion joint (aa) having imbedded therein flanges (cc) of a contraction joint (b^1) made of a flexible material, expanded in position to receive the concrete.

Figure 4 illustrates an expansion contraction joint in which the expansion joints (aa) have imbedded therein the flanges (cc) of a contraction joint (b^2), so shaped as to readily allow of the folding of the expansion joint (aa) and placed in superposed relation.

Figure 5 illustrates expansion joint (aa) having imbedded therein the flanges (cc) of contraction joint (b) the expansion joint (aa) being folded in a superposed relation for compact packing.

Figure 6 illustrates an expansion contraction joint in which the contraction joint (b^3) is circular in shape, having extended flanges (cc), expansion joint (a^1) being provided about the outer surface of the contraction joint (b^3), the center of the circular space being adapted to be filled with concrete.

Figure 7 illustrates contraction joint (b), having mounted upon its sides a centrally located expansion joint (aa).

Figure 8 illustrates an expansion contraction joint having the contraction joint (b) with extended flanges (cc) and placed upon the inner surface of the contraction joint (b) and expansion joint (a^2).

Figure 9 illustrates a contraction expansion joint, showing the contraction joint (b^4) with extended flanges (cc) the expansion joint (a^3) being attached to the inner face of (b^4).

Figure 10 illustrates an expansion contraction joint, consisting of the contraction joint (b) having extended therefrom flanges (cc) and mounted thereon expansion joints (aa), 5 and holes provided therethru as in (d).

Figure 11 illustrates a concrete pavement (e) poured about an expansion contraction joint (a).

Figure 12 illustrates the concrete pavement 10 (e) after it has set and contracted, developing a crevice (f) above the expansion contraction joint (a).

Figure 13 illustrates a concrete pavement 15 (e) after expansion has compressed the expansion contraction joint (a) so that it has elongated, as shown at (g), and gradually filled the crevice (f) which has developed in the pavement.

Figure 14 represents contraction plate (b) 20 with extending prongs for the purpose of fastening in the ground.

Figure 15 shows how this contraction plate (b) can be driven through an expansion joint (a), where it is desired to have only a slight elevation above the ground using narrow joints, spaced more frequently in road work.

In this figure the contraction joint (b) is used in combination with the expansion joint 25 (a). The forms of the invention herein shown but not claimed are specifically claimed in divisional applications concurrently pending with this application.

It may be readily understood that expansion joints may be used as contraction joints by using narrow widths of the expansion joint and placing them at suitable distances apart, so that the crevices will appear more frequently in the road, it being the function 40 of these expansion joints, which act as contraction joints, to cause the concrete to split or form a crevice wherever they are located.

The additional advantage in using an expansion joint as a contraction joint in this 45 respect is that after the crevice is formed, by using an expansion joint of expandable bituminous material these crevices can further be waterproofed, whereas when a steel plate is used this is not the case.

50 I claim:

1. A paving joint of changeable vertical dimension, comprising upper and lower slab separating portions, and an intermediate portion connecting the same adapted to be 55 varied in form to change the relation of the upper and lower portions.

2. A paving joint of adjustable vertical dimension, comprising upper and lower slab separating portions, and an intermediate 60 connecting portion deflected from the plane of the upper and lower portions and freely

flexible to permit the last named portions to be folded one upon the other for shipment.

3. A paving joint, comprising upper and lower slab separating portions, an intermediate connecting portion, and compressible material applied to both the upper and lower slab separating portions. 65

4. A paving joint, comprising upper and lower slab separating members composed of compressible material, and an intermediate portion of freely flexible material connecting 70 said upper and lower members and adapted to hold them in substantially the same plane while permitting them to be moved relatively 75 one to the other.

5. In combination a metal separating strip for concrete slabs, and a mastic crown for said strip, comprising a preformed strip of bituminous material having a slot therein 80 made to receive the upper end of the separating strip, said slot terminating short of the upper edge of said crown.

6. Expansion-contraction joint, comprising a metal strip having an intermediate 85 tongue and groove portion and flat upper and lower ends extending vertically from said tongue and groove portion, and a compressible mastic strip mounted to the upper vertical projecting end. 90

7. Expansion-contraction joint, comprising a metal strip having a horizontally projecting intermediate portion and upper and lower ends extending vertically from said intermediate projecting portion, and compressible mastic strips mounted to said upper and lower ends. 95

8. A preformed expansion joint, comprising a board-like body having a tongue on one side, a corresponding groove on the other side, and a flat portion arranged to one side of said tongue and groove, said joint embodying in its construction a thickness of plastic bituminous material reinforced by sheet material of lesser thickness. 100 105

9. An expansion joint, comprising upper and lower board-like portions of bituminous material and an intermediate tongue and groove portion yoking together said board-like portions and forming therewith an expansion joint. 110

10. An expansion joint, comprising upper and lower plastic, board-like members of bituminous material, and an intermediate member having horizontally presented tongue and groove, and yoking together said upper and lower members, said intermediate member also embodying in its composition bituminous material. 115

Signed at Chicago, Illinois, this 31st day of December, 1921.

ALBERT C. FISCHER.
